UNITED STATES PATENT OFFICE

JULIUS J. BEVINGTON AND EDWARD N. ROSENBERG, OF TOLEDO, OHIO

TRAFFIC-CONTROL RELAY AND SYSTEM

Application filed February 21, 1927. Serial No. 169,719.

This invention relates to traffic control systems of the type employing signals for regulating the flow of traffic at traffic intersections or crossings; and this application is a continuation in part of our prior application Serial No. 39,634, filed June 26, 1925, for "traffic control system."

Numerous systems have been designed for automatically controlling the flow of traffic at street intersections but in the majority of cases these systems, when electrically operated and when a considerable number are utilized along a street, require such amperage as to render them too expensive for practical purposes. Furthermore, it is quite essential for properly regulated traffic that the various signals be synchronously operated and heretofore traffic control systems have employed independent controllers which are so difficult to adjust for conjoint operation over extended periods of time that they have not proved especially satisfactory.

The objects of this invention are to overcome the above difficulties and to provide an automatic traffic control system operated by relays, to signal traffic to pass in say north and south directions while east and west bound traffic is signalled to stop, for a predetermined time, then to indicate for a predetermined time to all traffic, bound north, south, east and west, that the signals are about to be changed, then to signal east and west bound traffic to proceed and north and south bound traffic to stop for a predetermined time, and then to again throw on for a predetermined time the warning signals for all traffic that the signals are about to be changed, and then to signal traffic to pass north and south while stopping east and west bound traffic, as before, and so on continuously; provision being made to stop all traffic bound in all directions for the propose of giving right of way to fire engines and the like.

The invention is shown by way of illustration in the accompanying drawings in which

Fig. 1 is a front elevation of the relay part of the system, the two individual relays being shown in the position for permitting the passage of traffic bound either north or south or

east and west, and for stopping traffic bound respectively either east and west or north and south.

Fig. 2 is an elevation looking from the left of Fig. 1, this view being in section with respect to the lower relay along the line 2—2 of Fig. 1. 55

Fig. 3 is a plan view of either of the left side mercury switches and associated parts taken on the line 3—3 of Fig. 1. 60

Fig. 4 is a bottom plan view taken on the line 4—4 of Fig. 1.

Fig. 5 is a view partly in section of one of the left side mercury switches in open or neutral position, as seen from the right 65 thereof.

Fig. 6 is a sectional view on the line 6—6 of Fig. 1.

Fig. 7 is a view similar to Fig. 6 but showing the contacts immersed in the mercury. 70

Specifically, our relay device comprises a panel board 1 of slate or other insulating material adapted to support the parts fastened thereon. Each relay comprises electro-magnets consisting of coils 2, 3 wound in aiding relation to each other and each coil may have a suitable core, as 4 and 5 respectively; while cooperating with such coils is a polarized armature 6 mounted to pivot about the pin 7. under the influence of the above mentioned 80 coils. The pin 7 is suitably supported by the base plate 1. It will be apparent that one end of the armature 6 will be attracted upwardly while the other end thereof will be repelled downwardly when the current passes 85 through the coils in one direction, and that the armature will swing in the other direction upon reversal of such current.

An upwardly projecting bar 7^a is affixed to the armature 6 preferably symmetrically 90 thereof, such arm 7 supporting a forwardly projecting pin 8, said pin being caused to swing either to the right or to the left along an arc of a circle by the tilting of the armature 6. 95

Fixed to the base plate 1 is a supporting piece 9 on which the coils 2 and 3 are supported by the threaded bolts 10, the nuts 11 holding them in fixed position. A pivot pin 12 is attached to the supporting member 9.

directly over the pin 7 about which the armature 6 tilts, an arm 13 being pivoted to swing at the end thereof about the pin. This arm 13 comprises a flat portion 14 parallel with the base plate 1 and another flat portion 15 at right angles thereto, and it may be formed of a flat strip of metal by giving the same a quarter twist as indicated at 16.

The portion 14 has an elongated slot 17 therein through which the pin 8 projects and contacts loosely with the sides thereof. Two pins 18 and 19 are fastened to a connecting member or link 40 to be described later and these pins are located one on each side of the portion 15, leaving a little space for play of the arm between them.

Brackets 20 are firmly attached to the base plate 1 and these brackets comprise pivotal supports for the mercury switches 21 and 22. These switches have tapered holes at each end of the axes thereof which fit upon the tapered pins 23, 24 insulatably mounted upon the frame 20, one of these pins as 24 being adjustable toward or away from the pin 23 by means of the screw threads 25 thereon fitting within corresponding screw threads in the hole 26 through the support 20. After adjustment of the pin 25 it may be fixed in position by means of the nut 27. Each of these mercury switches has three contacts 28 therein arranged in the same axial plane and the ends thereof are substantially in line with each other. A substantially cylindrical casing 29, preferably of glass, surrounds the contacts and contains a properly sized globule of mercury 30 which is of sufficient depth to immerse the ends of the three contacts 28 when they point directly downwardly, and thus makes electric contact between them. Each of these contacts 28 is electrically connected with a coiled wire 31 which may lead respectively to a binding post 32, it being understood that the contacts are insulated from each other, as are the coiled wires. A metal collar 33 is sealed to the casing 29 at one end thereof and is in electrical contact with the right hand contact wire 28 as seen in Fig. 5, while another metal collar 34 is sealed to the glass casing 29 at the other end thereof and is likewise in electrical contact with the left hand contact wire 28 as seen in the same figure; while the central contact wire 28 is led in through the cylindrical side of the glass and is in electrical contact with the metal collar 35^a. The coiled wires 31 may be soldered to or otherwise electrically and mechanically attached to the collars. Surrounding the metal collar 34 is an insulating strip 35 and on this strip is fastened an arm 36 which is thus insulated from any conductive part of the mercury switch. For the sake of convenience the arm 36 comprises a split portion the two parts of which are held together by the screw 37. Holes 38 are provided in the lever members

36 through which pass bolts 39, said bolts also passing loosely through the ends of the link 40 which is the link carrying the pins 18 and 19 as previously described.

It will thus be apparent that when the coils 2 and 3 cause the left hand end of the armature 6 to move upwardly and the right hand end thereof to move downwardly as indicated in the top half of Fig. 1, the pin 8 will swing a short distance to the right and thereby cause the arm 13 likewise to swing to the right. The lower end 15 of this arm 13 will thereby strike against and move the pin 19 and link 40 to the right, thereby causing the mercury switches to rotate counter-clockwise. The contacts 28 are so arranged in the right hand mercury switch that they will be thereby immersed in the mercury and thus placed in electrical circuit with each other, while the contacts in the left hand mercury switch are so arranged that they will remain out of electrical contact with each other. If, on the other hand, the current be reversed in the coils 2, 3 whereby the left end of the armature 6 will be swung downwardly and the right end thereof upwardly, then the three contacts in the left mercury switch will be immersed in the mercury and electrical contact will thereby be made between them, but the contacts in the right mercury switch will then remain out of electrical contact with each other. It will thus be seen that when the current is passed through the coils in one direction only the right hand mercury switch will operate, while if this current be reversed then only the left hand mercury switch will operate. With no current passing through the coils both mercury switches are normally open, the arms 7^a and 13 then being normally in vertical position, and this may be caused either by attaching tension springs 41, 42 to the lower part of the arm 15 at one end of each, the other end of each spring being attached respectively to a flexible member, for example a thread 43, each passing through a hole in a screw threaded member 44 having a screw threaded connection with an insulating block 45 fastened to the base 1. Such block may also carry the binding posts 32, preferably in stepped relation as illustrated in Figs. 2 and 3, so that the binding posts may be as nearly as possible in line with the corresponding collars 33, 34 and 35^a. The springs 41, 42 may be used alone for the purpose of normally keeping the mercury switches in open position, or the arms 38 may be weighted and attached to the mercury switches in such relation that the levers will point downwardly simultaneously when the contacts in both mercury switches are so positioned that they are not immersed in the mercury. As a matter of fact either means for maintaining normal open position may be

used alone, or they may be used in combination with each other.

As indicated on Fig. 1 there are two like cooperating relays and associated parts, and for the sake of convenience one is located above the other on the base panel 1. Each of these relays operates either one of two mercury switches, so that both together operate four such switches. The three contacts of say the 10 upper left mercury switch may lead one to a source of power, one to say the north and south green "Go" lights, and the third to say the east and west red "Stop" lights; in which case the three contacts of the upper right mercury switch will lead one to the source of power, one to the north and south red "Stop" lights and one to the east and west green "Go" lights; and it is thus obvious that functioning of the upper relay will thereby effect a signal 20 that the north and south traffic should proceed while the east and west traffic should stop, or vice versa.

The lower relay and all its associated parts are the same as the upper relay and its associated parts, the only difference being that the contacts of the two lower mercury switches lead off to different circuits. The three contacts of say the lower left mercury switch may lead one to a source of power, another to the 30 north and south amber or "Caution" lights and the third to the east and west amber or "Caution" lights, so that when this switch is in operation all traffic is warned of an imminent change of signals. The three contacts 35 of the lower right mercury switch may then lead one to a source of power, one to the north and south red "Stop" lights and one to the east and west red "Stop" lights, whereby all traffic is warned to stop for a time to give 40 clear right of way to fire engines, ambulances and the like, when this switch is in operation. It is, of course, to be understood that any of the mercury switches may be applied to any one of the above mentioned set of signals as 45 desired, and that such system as is disclosed in our application Serial No. 39,634, above referred to, or any other desired system for operating the relays, may be used. Rotary switches which are used to cause a number of 50 circuits to operate in timed and sequential relation to each other are well known as are the systems in which they function, and any system or circuit maker and breaker which will cause the north and south green "Go" lights 55 and the east and west red "Stop" lights to operate for the desired time and thereafter cause all the amber caution lights to operate for the desired time and then the east and west green "Go" lights and the north and south 60 red "Stop" lights to operate for the desired time and then all the amber caution lights to again operate for the desired time and then the north and south green "Go" lights and the east and west red "Stop" lights to operate 65 as previously, and so on, are systems with

which our relay may be used to great advantage. That is, any device which will cause the current to flow through the upper coils in one direction for a given time, then discontinue such current and cause it to pass through the lower coils to close the lower left mercury switch for a given time, then discontinue such current and cause it to pass in the other direction through the upper coils for a given time, then discontinue such current and cause it to actuate the lower left mercury switch again, etc., etc., may be used. Automatically operating devices are well known for such purposes. Such operation as just described may be controlled by a main circuit switch, closing of which causes functioning to take place as just described and the opening of which causes such functioning to cease. Such a switch may be manually operated at the will of the operator but automatic operation is preferred. The switch which controls the circuit which causes the proper relay, say the lower, to operate in such manner that the mercury switch controlling all the red "Stop" signals in all directions will operate, for example by causing the left end of the lower armature to rise to close the lower right mercury switch, is preferably manually operated as the stopping of all traffic becomes necessary at unexpected times and is required for a previously unknown time. 70 75 80 85 90 95

The switch controlling the operation of all the "Stop" signals is best in closed or operative position only when the above mentioned main circuit switch is in open or inoperative position, and vice versa. Consequently it is preferred to combine these two switches into one manually operable double throw switch, so that when this switch is thrown to one side the signals operate and change automatically, while all the stop signals will be energized and there will be no automatic change when this switch is thrown to the other side. 100 105

The amber "Caution" signals may be made to flash on at the moment that the green "Go" and red "Stop" signals are extinguished, and vice versa, or the "Caution" signals may be flashed on before the "Go" and "Stop" signals are extinguished, and vice versa, so that there is some overlapping of signals. This may be adjusted as desired by suitably adjusting the rotary switch used to control the timed and sequential operation of the electro-magnets. 110 115

Binding posts 46 may be located upon the panel 1 for the purpose of making suitable connections to the various circuits, and connections therefrom may be made to the proper points by means of insulated conductors (not shown) upon the rear of the panel. 120

While the above description relates merely to one crossing for the purpose of convenience, it will be understood that a series of such mechanisms may be employed as illustrated for controlling the traffic at a number of crossings. It is not deemed necessary 125 130

to enter into an extended discussion of the other mechanism because in each the operation and construction are the same, and a common source of current may be used to operate like functioning parts simultaneously and such current for different crossings may be controlled by the same rotary switch. It is understood that similar signals may be made to appear along a series of crossings, or when desired the signals may be staggered as may be found suitable for existing conditions.

An outstanding advantage of our traffic control system heretofore described resides in the fact that it may readily be installed in cities or sizeable towns having electrical lighting circuit, and police and fire alarm circuits. It will be apparent that both the current from the lighting circuit as well as the current from the police and fire alarm circuit are utilized. In the operation of our traffic control system, it is quite evident that such traffic control system may be installed without the necessity of digging up streets to lay wires leading from other sources of supply, thereby reducing to a minimum the expense of installation inherent in systems requiring a source of current supply independent from circuits already installed.

It is also to be understood that the simultaneous operation of a number of control sets of the type described is insured because of the unique arrangement and manner of control, this being a distinct improvement over systems employing synchronous motors operating individual sets because it is practically an impossibility to maintain accurately conjoint operation of a number of such motors, and as a result the different signals do not operate together.

While we have described a construction which is the best form known to us at the present time, it is to be understood that numerous changes in details of construction, arrangement and operation may be effected without departing from the spirit of the invention, especially as defined in the appended claims.

Having described our invention what we claim is:

1. In a relay, a pair of electro-magnets, a lever pivoted at its upper end adjacent to the upper ends of said electro-magnets, an armature disposed at the lower ends of said electro-magnets and having an upwardly projecting bar, means to connect the upper end of the bar to a point intermediate the ends of the lever so as to rock the lever by the armature movements, a pair of rockable mercury switches disposed below the armature, an arm on each switch, a member pivoted to and connecting the arms, said lever having its lower end disposed adjacent to the connecting member, means on the connecting member to engage the said lower end of the lever to operate the latter, and means to normally hold the lever in vertical neutral position.

2. In a relay, a pair of electro-magnets, a lever pivoted at its upper end adjacent to the upper ends of said electro-magnets, an armature disposed at the lower ends of said electro-magnets, and having an upwardly projecting bar, means to connect the upper end of the bar to a point intermediate the ends of the lever so as to rock the lever by the armature movement, a pair of rotary mercury switches disposed below the armature, an arm extending outwardly from each switch, a member pivoted to and connecting the arms, the lower end of the lever extending below said connecting member, abutments on the connecting member engageable with opposite sides of the lower end of the lever, and coil springs below the member connected to opposite sides of the lower end of the lever to tension the latter.

3. In a relay, a pair of electro-magnets, a lever pivoted at its upper end adjacent to the upper ends of said electro-magnets, an armature disposed at the lower ends of said electro-magnets, and having an upwardly projecting bar, means to connect the upper end of the bar to a point intermediate the ends of the lever so as to rock the lever by the armature movement, a pair of rotary mercury switches disposed below the armature, an arm extending outwardly from each switch, a member pivoted to and connecting the arms, the lower end of the lever extending below said connecting member, abutments on the connecting member engageable with opposite sides of the lower end of the lever, and means to normally hold the lever in vertical neutral position.

JULIUS J. BEVINGTON.
